MACHINE FOR DRESSING REVOLVING
GRINDING WHEELSHarry Frederick Atkins, Old Fletton,
Peterborough, EnglandApplication August 25, 1934, Serial No. 741,432
In Great Britain August 29, 1933

4 Claims. (Cl. 125—11)

The invention provides the hereinafter described and claimed combination of parts embodied in a machine for dressing the operative face of a revolving grinding wheel, said machine being of the kind in which a dressing tool is controlled by the movement of a stylus against a stationary former of the exact shape to which the wheel is to be dressed.

The machine according to the invention has a stationary frame to rigidly support a former. A first compound slide is mounted upon the frame adjacent the former and carries a stylus to move in contact with said former. A second compound slide is also mounted upon the stationary frame and carries a dressing tool. The slide members of the two compound slides preferably move at right-angles to each other. Between the two compound slides a coupling means is arranged mounted in the frame, to cause said two compound slides to move in unison, in proportionate relationship, from the movement of the first compound slide governed by the contact of the stylus against the former.

The foregoing combination of parts in a machine is, generally speaking, arranged horizontally, that is to say, to provide a horizontal machine with the first compound slide on the top of the frame and the second compound slide below the frame, but both supported on said frame and with the coupling means working in bearings of the frame.

Also said machine may comprehend in its combination of parts means provided upon the first compound slide for adjusting the relative proportionate movements of the slide members of the second compound slide, and this means may be provided so that said adjustments may be either made simultaneously and collectively or independently with the object of governing the relative traverse of the respective slide members of the two compound slides.

The invention may also embody two crank shafts and cranks as part of the means for coupling the two compound slides to cause them to move in unison in proportionate relationship. The two compound slides need not be at right-angles to each other.

The machine according to the invention and embodying the combination of parts hereinbefore stated and hereinafter claimed is represented by the accompanying sheets of drawings.

Fig. 1 is a transverse sectional view.

Fig. 2 is a longitudinal sectional view of Fig. 1 on the dotted lines A, B.

Fig. 3 is a sectional plan of Fig. 2 on the dotted lines C, D.

Fig. 4 is a detail in sectional plan similar to Fig. 3 but illustrating a part of the coupling means.

Fig. 5 is a plan of a portion of Fig. 2 showing the stylus and former.

E indicates the first compound slide, and F indicates the second compound slide.

The frame 1 of the machine is provided with a pair of spaced apart parallel bearings 2 upon which is mounted to move longitudinally, in an anti-frictional manner by means of interposed balls, a slide member 3. This slide member 3 has a transverse slot 4 in which a slide member 5 is free to move in a direction at right-angles to the direction of movement of the slide member 3, this slide member 5 being supported anti-frictionally upon bearings 6 of the slide member 3. Thus the slide members 3 and 5, constituting the first compound slide E, move as a one-piece part in the longitudinal direction of the machine, but in the other direction at right-angles the slide member 5 only has movement. The slide member 5 carries a stylus 7 adapted to be moved in contact with the contour 8 of a former 9 rigidly supported upon the frame 1 by brackets 10. Said slide 5 carries as a rigid part of it a bar 11 having formed in its underside a longitudinal key-way 12 for the purpose as will be hereinafter described.

Mounted in bearings 13 forming part of the stationary frame 1 is a slide 14 connected to the slide member 5 by a key 15 to move transversely of the machine, this key 15 slidably engaging the longitudinal key-way 12 in such manner that when the slide member 5 makes longitudinal movement the key-way 12 slides idly over the key 15, whereas when said slide member 5 makes transverse movement the slide 14 always moves with it to an equal amount.

Rigidly but adjustably carried upon the underside of the slide 14 is a bar 16 formed with an under groove 17 inclined to the direction of movement of said bar 16, as shown clearly in Fig. 4. Slidably engaging this groove 17 is a slide block 18 carried by a crank pin 19 of a crank 20 whose shaft 21 is housed in vertical bearings formed in the frame 1. At the lower end of the shaft 21 is a crank 22 carrying a crank pin 23 engaging a slide block 24 which is slidably mounted in a transverse groove 25 of a slide member 26 mounted anti-frictionally in bearings 27 of the machine's frame 1 so as to be slidable in a longitudinal direction of said machine, this slide

member 26 being a part of the second compound slide F.

Rigidly but adjustably carried on the underside of the slide member 3 is a bar 28 formed with an under groove 29 inclined to the direction of movement of said bar with the slide 3 as shown in Fig. 3. Slidably engaging this groove 29 is a slide block 30 carried by a crank pin 31 of a crank 32 whose shaft 33 is housed in vertical bearings 39 of the machine's frame 1, the other end of this shaft being formed with a crank 34 carrying a crank pin 35 to engage a slide block 36 slidably mounted in a longitudinal groove 37 of a slide member 38 mounted anti-frictionally in bearings 39 of the slide member 26 to be movable in a transverse direction, this slide member 38 being the other slide member of the second compound slide F.

The dressing tool 40 is a reduced shape replica of the stylus 7 and is carried by a holder 41 mounted within a boring of the slide member 38. The revolving grinding wheel to be dressed is indicated at 42 and is protected by a guard 44 forming a stationary part of the machine's frame.

The operation of the machine, having regard to the position of the stylus in relation to the former as illustrated in Fig. 5, is as follows:

The movement of the stylus 7 along the contour 8 of the former 9 (by hand operation of the knob 59) is permitted by the combined longitudinal and transverse movements of the slide members 3 and 5, respectively, of the first compound slide E, that is to say, if the stylus is moved from the position indicated in full lines in Fig. 5 to a position 60 indicated in dotted lines in this figure, the movement of the stylus along the contour 8 of the former 9 is a combined movement of the slide member 5 to the extent of the depth of the thread and of the slide member 3 to the extent of half the pitch of the thread, so that in this plane of movement the stylus has a universal traverse in contact with the former. During the movement of the slide member 5 in one of its directions the key 15, the slide 14, the bar 16, and the groove 17 all move with it to thereby cause the shaft 21 to be rocked and the slide members 26, 28 to be moved in one direction, as shown in the drawings, at right angles. When the slide member 5 is moved in its other direction the slide member 3 is moved with it and the key-way 12 in the bar 11 will slide idly over the key 15 so that no motion is transmitted to the slide 14. The bar 28 and groove 29 are carried by the slide member 3 and therefore as said slide moves the groove 29 is carried with it and will partly rotate the shaft 33 to thereby impart movement to the slide 38 in a direction at right angles to the direction in which the crank shaft 21 moves it.

The combined movement of the slide members 26 and 38 in the one direction and the movement of the slide member 38 in the other direction causes the dressing tool 40 to follow a path exactly the same as the path described by the stylus over the former but with a reduced amount of traverse dependent upon the inclination of the grooves 17 and 29 and the throw of the cranks 20 and 22 and 32 and 34.

Separate means are provided for varying the angle of inclination of the grooves 17 and 29 comprising for each adjustment an internally screw threaded sleeve 45 and a screw threaded pin 46 adapted to co-operate in such a manner as to, in the one case, clamp the slide 14 to the

bar 16 and in the other case clamp the slide member 3 to the bar 28. To allow the inclination of the groove 17 to be altered quickly and accurately to another angle holes 47 and 48 are provided in the slide 14 and holes 49 and 50 are provided in the bar, said holes being relatively positioned but by alignment of the holes 47 and 49 or 48 and 50 different angles of inclination of the grooves 17 are obtained and this inclination fixed by the insertion into either pair of said aligned holes of a dowel peg 51 which can be removed and applied by a tool applied to its screw threaded bore 52. A soft metal insert 53 in which the holes 47 and 48 are provided forms part of the slide 14. To allow the inclination of the groove 29 to be altered quickly and accurately to another angle holes 54 and 55 are provided in the slide member 3 and a hole 56 is provided in the bar 28. Said holes 54 and 55 are relatively positioned but by alignment of the holes 54 and 56 or 55 and 56 and the insertion of a dowel peg 57 different angles of inclination of the groove 29 are obtained. A bracket 58 constitutes the base of the table 1.

To change the inclination of the grooves 17 and 29 the respective dowel pegs are first withdrawn, the respective clamping devices, such as 45 and 46, are loosened and then the bars 16 and 28, about the clamping devices as their pivots, are partially rotated until the dowel pegs 51 are inserted into the newly aligned holes, after which the clamping devices are screwed up tightly to rigidly fix the bars 16, 28 to their respective slide and slide member.

The proportionately reduced relative movement between the stylus 7 and the dressing tool 40 may be varied by a means alternatively, or in addition, to the means hereinbefore described, consisting of varying the throw of any, or all of the cranks 20, 22, 32 and 34, by providing a plurality of holes in the said cranks and by providing on each of the slide-blocks 18, 24, 30 and 36, a pivoting pin adapted to engage one of the holes in its associated crank.

It is to be understood that the proportionately reduced relative movement between the stylus 7 and the dressing tool 40 may be different in the longitudinal and transverse directions, and this may be effected by inclining the grooves 17 and 29 to relatively different angles whilst maintaining the relative throw of the double cranks 20, 22 and 32, 34, the same, or by altering the relative throw of the double cranks 20, 22 and 32, 34, whilst maintaining the angles of the grooves 17 and 29 the same.

The dressing tool 40 is illustrated as operating at right angles to the stylus 7, but the machine may be arranged such that said dressing tool operates parallel to or at any angle to said stylus.

Having now described my invention, what I claim and desire to secure by Letters Patent is:

1. Machine for dressing the operative face of a revolving grinding wheel comprising in combination a stationary frame, a former rigidly supported by the frame, a first compound slide mounted upon the frame adjacent the former and carrying a stylus to move in contact with the former, a second compound slide also mounted upon the frame and carrying a dressing tool, and means coupling the two compound slides to cause them to move in unison in proportionate relationship.

2. Machine for dressing the operative face of a revolving grinding wheel comprising in combination a stationary frame, a former rigidly

supported by the frame, a first compound slide mounted upon the frame adjacent the former and carrying a stylus to move in contact with the former, a second compound slide also mounted upon the frame and carrying a dressing tool, means coupling the two compound slides to cause them to move in unison in proportionate relationship, and means provided upon the first compound slide for adjusting the relative proportionate movements of the members of the second compound slide.

5 3. Machine for dressing the operative face of a revolving grinding wheel comprising in combination a stationary frame, a former rigidly supported by the frame, a first compound slide mounted on top of the frame adjacent the former and carrying a stylus to move in contact with the former, a second compound slide also mounted below the frame and carrying a dressing tool, and means comprising two crank shafts and

cranks supported in the frame for coupling the two compound slides to cause them to move in unison in proportionate relationship.

4. Machine for dressing the operative face of a revolving grinding wheel comprising in combination a stationary frame, a former rigidly supported by the frame, a first compound slide mounted on top of the frame adjacent the former and carrying a stylus to move in contact with the former, a second compound slide also mounted below the frame and carrying a dressing tool, means comprising two crank shafts and cranks supported in the frame for coupling the two compound slides to cause them to move in unison in proportionate relationship, and means provided upon the first compound slide for adjusting, through the crank shafts and cranks, the relative proportionate movements of the members of the second compound slide.

10 15 20 HARRY FREDERICK ATKINS. 20
